UNITED STATES PATENT OFFICE.

SAMUEL VAN BUREN ESSICK, OF BROOKLYN, NEW YORK.

PRINTING-TELEGRAPH.

SPECIFICATION forming part of Letters Patent No. 443,134, dated December 28, 1890.

Application filed November 7, 1888. Serial No. 290,247. (No model.)

To all whom it may concern:

Be it known that I, SAMUEL VAN BUREN ESSICK, a citizen of the United States, residing at Brooklyn, county of Kings, and State of New York, have made a new and useful invention in Printing-Telegraphs, of which the following is a specification.

My invention is directed to improvements upon inventions disclosed in prior patents granted to me as follows: No. 279,550, dated June 19, 1883; No. 365,059, dated June 21, 1887, and No. 383,450, dated May 29, 1888, but more particularly to improvements upon a later invention disclosed in a pending application filed by me on the 5th day of July, 1890, and bearing Serial No. 357,818.

The objects of the present invention are, first, to adapt apparatus of the generic type disclosed in the aforesaid application to closed circuits; second, to provide means for releasing the paper-carriage at any point of its forward progress; third, to provide an improved form of a mechanical pole-changer for automatically reversing the main-line currents; fourth, to provide the several details of construction and the general arrangement of parts, circuits, and connections, as herein-after described, but particularly pointed out in the claims which follow this specification.

In the invention disclosed in my application, Serial No. 357,818, above referred to, the mechanically-operated pole-changers are caused through the operation of two banks of keys to manipulate circuit-changing levers and thereby vary the current tension on the line, and to interrupt the main-line current, respectively.

The general arrangement of the circuits and transmitting apparatus of the present application differs from that disclosed in said application in that the two sets of key-levers are made to mechanically control the pole-changer by holding it from rotation after the depression of each key until it is allowed to proceed on the depression of a succeeding key or on the release of all or any of the keys.

In order that my invention may be clearly understood, reference is had to the accompanying drawings, in which like figures and letters of reference represent like parts whenever used.

Figure 1 is a plan view of the entire apparatus embracing the transmitter and receiver attached to a common base. Fig. 2 is a side elevation and partly-sectional view of Fig. 1 as seen looking from right to left. Fig. 3 is a side elevational view, also partly in section, of the entire apparatus as seen looking at Fig. 1 from left to right. Fig. 4 is a perspective view of the printing mechanism. Figs. 5 and 6 are elevational and plan views thereof. Fig. 7 is a detail end elevational view of the key-levers in connection with the circuit-manipulating switch operated thereby. Fig. 8 is a diagrammatic view of the electrical circuits with the switches shown in position for transmitting, the line-circuit also being shown with the receiver at the distant station.

Referring now to the drawings in detail, A represents the base or support of the entire apparatus.

B B' B² are the sides of the frame of the entire apparatus, B and B' being joined together by metallic cross-bars C C' C² C³ C⁵, while the side bar B² is secured to B' by the arms 9.

G G' G² G³ and H H' H² H³ is a train of gearing impelled by a spring or weight driven drum, the gear-wheel G³ meshing with the pinion H³, carried by a rotary shaft 17, journaled to the frame of the machine and provided with a series of spirally-arranged pins P.

L' L' L' and L² L² L² are key-levers arranged in two set or rows, one set corresponding to the keys K' and the other to the keys K², said banks of keys being disposed as shown in Fig. 1. The key-levers L² are provided with angle-pins adapted to bear against the key-levers L' on their downward stroke and carry said key-levers with them.

g² is a pivoted switch-bar secured to the sides of the frame B B' and carrying a switch-block 88, secured thereto by an insulated neck 87. (See Fig. 7.)

On the left-hand end of the shaft 17 is an escapement-wheel 21, having half as many teeth as there are characters upon the type-wheel T, where the type are arranged in two rows. This escapement-wheel, and hence its shaft 17, is held from rotation by a two-armed escapement-pallet 49 on the upper end of a pivoted armature-lever a, situated between the poles of main-line polar-magnets o' o²,

provided with adjustable screws 50 51 for regulating the accurate adjustment of the magnets and their intermediate armature, said magnets and adjustment-screws being 5 secured to the side B of the frame.

Just in the rear of the escapement-wheel 21 is a ratchet-wheel 22, provided with twice as many teeth as are found upon the escapement-wheel 21, or one escapement-tooth for 10 each letter on the type-wheel T. The ratchet-teeth of the ratchet-wheel 22 are adapted to vibrate a circuit-lever L, pivotally secured to the side of the frame B by a bracket 72. An additional ratchet-wheel 600, having the 15 same number of teeth as the ratchet-wheel 22, is carried by the shaft 17, and a detent or pawl 610, carried by the armature-lever of an electro-magnet 262, which lever is held in its upward position by a spring 630, is adapted 20 to arrest the rotation of the shaft 17, as will be described later on.

At the distant end of the shaft 17 is still another ratchet or escapement wheel 23, (see Fig. 2,) having the same number of teeth as 25 the escapement-wheel 21, and adapted, when the shaft 17 is rotated, to impart a vibratory motion to a vibratory pole-changer D', pivotally secured to the frame by a bracket T', its lower extremity I² having pallet-arms e³, which 30 partake their vibratory motion from the escapement-wheel 23, the upper portion of the pole-changer D' consisting of two sets of elastic or yielding arms e e', having electric contacts for reversing the circuit through the 35 contacts c c' d d', (see Figs. 2 and 8,) so that as the shaft 17 rotates the direction of the current from the line is continuously reversed by the pole-changer D'.

Referring again to the key-levers beneath 40 the key-board K and to Figs. 2 and 3, p³ is a pivoted locking-bar having a locking-notch extending beneath the shouldered ends of all of the key-levers L' of the first bank of keys K' and adapted to lock any one of said key-levers in its lowermost position when it is depressed and to bring its free end into the path of that one of the pins P on the shaft 17 which corresponds to it, so as to check said shaft from further rotation until released by 45 50 the depression of a second key. This locking-bar p³ is held in its forward or locked position by a spiral spring p⁵, and each of the key-levers L' L' is provided with a leaf-spring y, which tends to restore it to normal position 55 after any one of the keys K' K², acting through its stem r, has depressed said key-lever.

p⁴ is a releasing-key secured to the locking-bar p³ and adapted when depressed to release the key-lever last held down, and thereby allow 60 the apparatus to run continuously so long as said lever p⁴ is held.

This constitutes the entire transmitting apparatus, except such portions as necessarily embrace the electrical features of the instrument, which will be described in connection with the diagram illustrated in Fig. 8 in giv-

ing a general description of the mode of operation.

Many features of this transmitter are essentially similar to those of the transmitter 70 described in my application above referred to, notably the power-impelled shaft 17 with its spirally-arranged pins, and the polar main-line magnets o o', with their escapement, and the local-circuit connections between the vi- 75 brating circuit breaker or lever L and the printing and shifting magnets of the receiving apparatus.

The essential difference between the transmitting apparatus herein described and that 80 disclosed in my application Serial No. 357,818 lies in the fact that in the present apparatus I design and adapt the entire system to a closed-circuit main line and to this end I have arranged the key-levers, as already described, 85 so that the depression of any one key-lever will cause the shaft 17 to stop rotating when the pin P corresponding to that key-lever strikes the depressed lever, and have adapted main-line relays 262 for stopping the rotation 90 of the shafts 17 at both stations on the depression of any one of the second bank of keys, so that the type-wheel shaft may be shifted and printing effected from the second row of characters, after which the type-wheel 95 shaft is restored, all as will be fully described in connection with the description of the mode of operation.

I will now describe very briefly the printing apparatus, which is not materially different 100 from that disclosed in my application Serial No. 357,818, in its essential features, except as to the mechanism for releasing the paper-carriage at any portion of its journey, instead of accomplishing that function when 105 at the extreme end thereof.

In the present invention, as in that described in my application above referred to, there is a single printing-magnet M', with a second type-wheel-shifting magnet M², both 110 under the control of a local battery BA, and a vibrating circuit-closer L, operated by the rotation of the shaft 17.

95 is a paper-carriage adapted to be carried back and forth on rollers J' J' in the grooved 115 cross-bars C' C⁵.

105 is a spring returning-drum secured to the frame by a bracket b².

h² is a cord for carrying the carriage in one direction.

p and p' are the propelling pawl and lever attached to the arm v' of the armature-lever and act in the rack-teeth n of the propelling-rack 102 for advancing it step by step as the magnet M' is energized and de-energized. 120

o o' is a retaining-lever and pawl, the free end of which lever lies in the path of the lower end of the pawl p'.

The arm 104 of the armature-lever a' has attached to its free end a link 109, the 130 other end of which is secured to the platen-lever 108, pivoted to the frame on a vertical

shaft 107 and provided with a spiral retractile spring v^2 , the printing-pad 110 being secured to the free end of the platen-lever 108.

On the link 109 is a shoulder r^2 , adapted to 5 impart a rotary motion to the rock-shaft 36 through the agency of a lever r^3 , acting against the stress of spring s^3 , which unites the arm 38 of the rock-shaft 36 with the cross-bar C' through the agency of a fixed standard s^2 .

10 37 is a locking-lever, and 34 a unison-lever, secured by a common bearing to the rock-shaft 36, the locking-arm 37 resting normally on the free end of the armature-lever 111, which in turn bears lightly against the type-wheel shaft 30, adapted to be slid to the right (see Fig. 4) against the pressure of the spiral spring s' , which bears at one end against the 15 frame B and the other against a cap V.

20 35 is the unison-worm into which the unison-arm 34 gears when the locking-arm 37 falls behind the armature-lever 111 in its forward or locking position.

25 96 and 97 are the paper-feeding rolls journaled in the paper-carriage 95, the former having a ratchet-wheel 98, the teeth of which are adapted to receive the pawl 99, pivotally secured to a pivoted feeding-lever 100, whereby the paper is fed forward a line at a time each time the lever 100 is brought into frictional 30 contact with the adjustable angular arm 101, secured to the cross-bar C'.

35 The carriage-propelling pawl-lever p is pivotally secured to the free end of the arm v' , carried by the armature-lever a' , and is provided with a spring z^4 , fixedly secured to the free end of the lever v' , and tends normally to hold the lever p , and hence its pawl p' , in working contact with the rack-teeth n of the rack 102.

40 40 a^2 is a locking-latch pivoted to the arm v' , its free end having a beveled shoulder adapted to lock against a similar beveled shoulder on the short arm z^3 of the pivoted propelling-lever p . This locking-latch a^2 is brought into 45 action by a fixed lug on the upper side of the free end of the rack 102, which strikes it when the carriage reaches its extreme limit, thereby forcing the beveled shoulder of the locking-latch against the corresponding beveled shoulder of the propelling-lever p , releasing 50 its pawl from the rack-teeth n , and at the same time releasing the locking-pawl p' and allowing the carriage to run back to normal position.

55 i' is a lug on the rack 102, adapted to release the latch a^2 when the paper-carriage returns to its normal position, the direct action of the spring-drum 105 and its cord h^2 being such as to cause the lug i' to give a 60 sufficient blow to the latch a^2 to detach it, thereby allowing the spring z^4 to restore the pawl-lever p into operative relation with the rack-teeth n .

65 The printing mechanism thus far described is almost identically the same as that disclosed in my application Serial No. 357,818, and is only described here in order that I may more

accurately describe the apparatus which I use for causing the paper-carriage to return to its normal position under the stress of the 70 spring-drum 105 and cord h^2 at any portion of its journey, instead of at the end thereof, as is the case in the apparatus disclosed and claimed in the prior application above referred to.

75 The mechanism which I utilize for accomplishing the release of the paper-carriage at any portion of its journey consists of a pivoted lever l , (see Figs 2, 4, and 5,) secured to the side of the frame B' and having project- 80 ing teeth on one of its free ends adapted to come into mechanical connection with a pin g^6 on one of the gear-wheels G^3 each time that said gear-wheel makes a complete revolution, which occurs about once in two revolu- 85 tions of the type-wheel, the pinion H^3 and gear-wheel H^4 , connected, respectively, to the shaft 17 and type-wheel shaft, having both the same number of teeth. On the other end of this lever l is a long pin l' , adapted to lie 90 in the path of the locking-latch a^2 after the gear-wheel G^3 has made two complete revolutions. The lever l is provided with a leaf- 95 spring, which normally tends to lift the end which carries the pin l' into its upward position.

100 l^3 is a pivoted locking-lever secured to the frame B', and having a spring l^5 at its lower end which normally tends to press its upper end in the direction of the arm v' , carried by 105 the armature-lever a' , and it has secured to its inner side a projecting lug l^4 , which comes in contact with the arm v' each time the armature-lever a' is drawn forward. During 110 the first revolution of the gear-wheel G^3 , sup- 115 posing it to be rotating in the reverse direction of the hands of a watch, as seen looking at Fig. 2, the lever l is tilted forward, so that its free end rides behind the first one of two notches in the locking-lever l^3 . (See Figs. 1 and 120 4.) On the next revolution of the gear-wheel G^3 the pin g^6 rides against the second tooth or notch on the free end of the lever l and carries it forward an additional step, thus allowing the second notch, which is on the inner face 125 of the pivoted lever l^3 , to engage that end of the lever l , at the same time placing the long pin l' , borne by the arm l , directly in the path of the free end of the locking-latch a^2 , so that the first time the armature-lever a' is 130 drawn forward by the printing-magnet M' the pin l' will force the latch a^2 to the left, (see Fig. 5,) bringing the beveled shoulder thereof into locking position against the beveled shoulder of the short arm z^3 of the pivoted lever p , at the same time releasing the pawl p' and the locking-pawl o' and holding them in their released position until the carriage runs back to its normal or starting position. At the same time the arm v' is drawn 135 forward the lug l^4 , carried by the lever l^3 , is caused to force the lever l^3 to its rear position, thereby unlocking the pivoted lever l and allowing it to return to its original or

first position under the stress of the leaf-spring, (see Fig. 2,) carrying the pin l' out of the path of the latch a^2 . When the carriage runs back, the lug i' on the rack 102 strikes 5 the latch a^2 a blow and restores it to the position shown in Fig. 5, so that the propelling and holding pawls are in operative relation with the rack under the stress of their springs z^1 and r' .

10 Referring now to Fig. 8 of the drawings, which illustrates diagrammatically all of the electrical connections in the transmitting and receiving apparatus at both stations, connected by a main line earthed at each station, it will be seen that the main-line battery 60 is divided into two parts $z z'$, and that a polar relay N is connected to the switch S on one side and to the earth at E^2 on the other, so that as its armature vibrates it will alter- 15 nately place the respective portions $z z'$ of said battery in connection with the polar magnets $o' o^2$ when the switch S is placed upon its contact and the multiple switch M is placed in the reverse position to that shown 20 in the drawings. The apparatus at each station is the duplicate of that shown in the diagram, and the only difference in the electrical connections at the two stations when one operator is transmitting and the other 25 receiving is to be found in the location of the switches M and S, they being shown in the diagram in the position for transmitting. Under this condition of affairs the main-line battery 60 and the supplemental battery z^2 30 constitute the entire transmitting-battery for sending the current-impulses through the main-line magnet $o' o^2$, the switch S, and polar relay N, the battery 60 at the distant station being converted into a local battery for 35 the time being, controlled by the armature of the polar relay N at that station, the polar relay N at the home or transmitting station being normally out of circuit, as shown at switch S.

40 With this understanding of the operative relation of the circuits I will now proceed to describe the mode of operation of the entire apparatus. Starting from the earth E, the first 45 impulse is sent from the line as follows: Suppose that the main-line battery 60 is normally in circuit with its copper or positive pole to line, and the pallets 49 at the home or transmitting station are in the position shown in Figs. 3 and 8, locking the shafts 17 50 from rotation at both stations until the next impulse of reversed polarity is sent over the line, the shaft 17 at the transmitting-station rotating continuously, and hence causing the pole-changer D', operated by the ratchet-wheel 55 23, to successively reverse the currents upon the line until stopped by the depression of some one of the keys, as will be described. Starting from the earth E, the circuit is therefore as follows, as indicated by the tailless 60 arrows: through the pole-changer D', between the points e and d' , to contact-spring 760 on the upper side of the circuit-changing

block 88, thence to switch-lever S^6 of main-line switch M, the negative pole of the battery 60, to switch-lever S^5 of switch M, thence 70 to contact-spring 640, thence to contact d^3 , (see Fig. 7,) thence through the pole-changer by contacts e and d , thence to switch-lever S^2 of switch M, thence to main-line magnet 262, thence to switch-lever S^4 through the 75 polar magnets $o' o^2$, thence to switch-lever S^3 of switch M, and finally to line to the distant station, where it enters the receiver by way of the switch-lever S^2 , (supposing for the time being that the switch M is reversed,) thence 80 through the distant main-line magnet 262, through the switch S, (that switch having been turned on its contact, as before indicated, at the distant station,) through the polar relay N to earth at E^2 , and back to the 85 starting-point through the home earth at E. This impulse thus sent over the line reverses the position of the pallet-lever 49 at the home station and causes the polar armature of the polar relay N at the distant station to assume 90 a position on the contact 86, thereby closing the circuit of that portion z of the battery 60 through the polar magnets $o' o^2$ and switch-levers $S^4 S^3 S'$ and earths E and E^3 , thus imparting to the pallet 49 at the distant station 95 a motion in the reverse direction, allowing the shaft 17 at that station to make one advance step forward. The forward advancement of the shaft 17 at the transmitting-station causes the pole-changer D to immediately reverse its position and to bring the contacts $e' c c'$ together, first breaking the circuit between the contacts e and $d d'$. The circuit from the earth E through the main-line battery 60 at the transmitting-station is 100 now in the reversed direction of the tailless arrows after it reaches the pole-changer D, as follows: between the points e' and c' , to the outer portion of the contact d^3 , (see Fig. 7,) to spring 640, to switch-lever S^5 , 105 positive pole of the main-line battery 60, to switch-lever S^6 , to spring-contact 760, back to the pole-changer on the rear side of contact d' , through the pole-changer, between the contacts $c e'$, to switch-lever S^2 of switch M, 110 to main-line magnet 262, switch-lever S^4 of switch M, main-line polar magnets $o' o^2$, switch-lever S^3 of switch M to the main line, where it enters the receiver, as before, through the switch-lever S^2 , (said switch being on its 115 left-hand contact at that station, as before described,) and passes through the main-line electro-magnet 262 to the switch S, (said switch S, as before, being on its contact,) and through the polar relay N to earth at E^2 . This reverses 120 the position of the armature of the relay N at the receiving-station, and hence places said armature in contact with contact 87, thereby closing the circuit of the portion z' of the battery 60 at the distant station through 125 the polar magnets $o' o^2$ and switches $S^4 S^3 S'$ and earths E^3 and E in a reversed direction to the current which was formerly sent by 130 that portion z of the battery 60. This re-

versal of the current of the portion z' of the battery 60 immediately reverses the position of the pallet 49 of the receiving-instrument and allows it to advance another step. Hence 5 in obedience to the successive current reversals of the transmitting-battery 60, through the agency of the mechanically-impelled pole-changer D', the home polar magnet o' o² is caused to continuously vibrate the home pallet 49 and allow the shaft 17 to run continuously, while the pallet 49 of the distant polar magnet o' o² is caused to continuously vibrate through the agency of the locally-reversed currents due to the portions z z' of the temporary local battery 60. As the two shafts 17 are thus caused to rotate continuously, the circuit-breaking levers L at both stations are kept in continuous vibration by the ratchet-teeth on the ratchet-wheels 22, thereby preventing the closure of the circuits of the local batteries BA at both stations until both of said shafts are checked. These alternately-reversed currents are not sufficiently strong to effect the armatures of the main-line magnets 262, and these armatures at both stations will only respond when an increased battery-current from the supplemental battery z² is placed upon the line, as will be described later on. Suppose now that both of 20 the shafts 17 are rotating continuously and that the type-wheels T are running in unison. I will first presume that it is desired to print from one of the levers in the upper bank of keys K'. On depressing such key 25 to its full limit its shaft v causes the lever L', located beneath it, to be depressed against the influence of the spring y, (see Fig. 3,) and it is locked in that depressed position under the locking-bar p³. Its free end now 30 lies in the path of that particular pin P which corresponds to it on the shaft 17. When the pin P is checked in its rotation by the end of the lever L', the shaft 17 ceases to rotate, and immediately the tooth or lug on the under 35 side of the circuit-lever L drops into one of the teeth of the ratchet-wheel 22 under the influence of a spiral retractile spring, as shown in Fig. 3, thereby closing the circuit of the local battery BA between the contact-points t and t', through the wires w', armature-lever 630, and printing-magnet M'. This 40 causes the armature-lever a' to be drawn forward (see Figs. 4 and 5) and to bring the platen 110, borne by platen-lever 108, firmly 45 against the paper, and forces it into contact with the letter to be printed. The same forward motion of the armature-lever a' retracts the carriage-propelling pawl a distance of one of the rack-teeth n, and the holding-pawl o' 50 retains the rack during the time that the pawl p' is being withdrawn. If the type-wheels are in unison, the moment that the shaft 17 at the transmitting - station has stopped vibrating the armature of the polar relay N at the receiving-station is also checked in its vibrations and rests on that one of the contacts 86 or 87 which will give to the pallet 49 of the magnet o' o² the proper impulse, and thus leave said pallet in that position until the transmitter is again started. The shaft 70 17 at the receiving-station being thus checked by the pallet-lever 49, printing is effected by the local battery BA and printing-magnet M', as was described in connection with the duplicate apparatus at the transmitting-station. 75 Suppose now that it is desired to print from the second row of letters on the type-wheel T. The desired key K² of the second bank of keys is depressed, and the act of depressing this key causes the locking-bar p³ to release 80 the lever last depressed and to lock that particular one of the levers L' which lies in the path of the angular arm on the lever L² just depressed. The lever L² also during this downward motion causes the tilting frame g² 85 to be carried forward, and thus causes the increased current to be sent upon the line as follows: Starting from earth E, as before, the current passes in a reverse direction to the tailed arrows, to the pole-changer D, through 90 the contact-spring 840, additional batteries z², copper pole of battery 60, through switch-arm S⁶ to spring 760, thence to spring 860, to the pole-changer, through the contacts d e to switch-arm S³, to relay 262, to the 95 switch-arm S⁴, to the polar electro-magnet o' o², to the switch-arm S³, to line, and to the receiving-station through the receiving-relay N in the same manner as before described. This increased strength of current sent over 100 the line for an instant of time, during which the key-lever L², and hence the tilting frame g², is held down, causes the armature-levers 630 of the main-line electro-magnets 262 at both stations to be drawn forward on their 105 front contact-stops and to temporarily check the rotation of the shafts 17 at both stations. (See Figs. 3 and 8.) At the same time it momentarily closes the circuits of the local batteries BA at both stations through the type-wheel-shifting magnets M² and causes the type-wheel shafts to be shifted under the influence of the armature-levers 111 a sufficient distance to place the second row of type on each wheel in alignment with its printing-pad, and at the same time the locking-levers 110 115 37 at both instruments are automatically caused to lock the levers 111 in their forward position under the stress of the spring s³, acting on lever 38. As soon then as the key-lever K² is released the armature-levers 630 at both stations assume their normal positions, and the shafts 17 rotate until the pin P which corresponds to the lever depressed at the transmitting-station checks the transmitting-shaft, when the circuit-levers L at both stations cease vibrating and close the printing-magnet circuits from the local battery BA through the printing-magnets M', thereby causing the printing-plantens at both stations 120 125 to impress the letter upon the paper. The same act causes the links 109, attached to arms 104, to release the locking-levers 37 through the agency of levers r³ and rock-

shafts 36, and as a result the type-wheel shafts of both instruments slide back to their original positions for printing from the first row of type. Printing is thus effected from either 5 row of type at will, and when it is desired to bring the instruments both to unison the operator places his finger on the blank white key shown at the bottom of the key-board K in Fig. 1, said key being connected to the tilting frame g^3 only. This causes the type-wheel shafts of both instruments to be locked in their forward positions and brings the unison-levers 34 in operative relation with the worm-gears 35. He then releases the blank 10 key and touches the key p^1 , which is connected with the locking-bar p^2 , and thereby releases any of the key-levers which may have been before depressed, thus allowing the instruments to run continuously until brought 15 to unison, after which he depresses the dot or period key F, when both of the instruments will imprint a period upon the paper at both stations. The apparatus is now ready to proceed, and printing can be effected from either 20 25 bank of keys, as fully described.

I make no claim in the present application to the printing apparatus illustrated in Figs. 4, 5, and 6, except in so far as to claim said apparatus in combination with the devices 30 35 40 45 50 55 60 herein described for releasing the paper-carriage at any portion of its journey; nor do I claim in this application any of the features connected with the transmitter, wherein the rotary shaft 17 is operatively connected with the detaining-pallet 49 and two banks of key-levers, all of such features being claimed in connection with my pending application, Serial No. 357,818, above referred to; nor do I claim in the present application a transmitter having a series of key-levers, a power-driven shaft, and a locking-bar adapted to lock any one of said key-levers in its depressed position and to hold it until it is released, in combination with an escapement for controlling the rotation of the shaft, a series of stop-pins carried by the shaft and lying in the path of the key-levers when depressed; neither do I claim herein a revolving shaft having stop-pins corresponding in number with the characters on the type-wheel of the receiver, a pole-changer operatively connected with the shaft, key-levers, one for each pin, adapted to engage said pin when depressed, check the shaft in its rotation, and hold it until again released by the raising of said key, and an escapement which regulates the forward motion of the shaft, as this subject-matter constitutes the major portion of a divisional application filed by me in the United States Patent Office on the 18th day of September, 1890, and bearing Serial No. 365,320.

I do not limit myself to the specific mechanism herein described and shown for effecting the printing from two rows of type upon 65 a single type-wheel, nor to the mechanism for liberating the paper-carriage at any por-

tion of its journey, as I believe I am broadly entitled to generic claims directed to mechanism for performing these functions.

Having thus described my invention, what I claim, and desire to secure by Letters Patent of the United States, is—

1. In a printing telegraphic receiver, a type-wheel driven by a train of gearing, a paper-carriage having advancing and restoring 75 mechanism, and a releasing device mechanically connected to one of the gear-wheels for automatically releasing the paper-carriage at any point of its excursion, substantially as described. 80

2. In a transmitter for printing or analogous telegraphic systems, a series of key-levers, a locking-bar adapted to lock any one of said key-levers in a depressed position, a power-driven shaft controlled by an escapement, a 85 series of stop-pins carried by the shaft, one for each lever, a pole-changer operatively connected to the shaft, an electrical generator, and circuit-connections, as described, whereby the shaft will rotate and cause the pole- 90 changer to send reverse currents over the line so long as none of the keys are depressed and will be held from rotation after any key is depressed until it is again released, substantially as described. 95

3. In a transmitter for use in a printing telegraphic or analogous system, a power-impelled shaft operatively connected to a pole-changer and a main-line battery, an electro-magnet located in the main line but irresponsible to the 100 aforesaid battery, and a second battery with connections for adding it to the first-named battery, in combination with a detent carried by the armature of said magnet and a ratchet carried by the shaft which controls the operation of the pole-changer, whereby said pole-changer is checked in its operation on the transmission of all of the battery-current, substantially as described. 105

4. In a system of printing or analogous telegraphy, a transmitter having two banks of keys, a power-impelled shaft operatively connected to a pole-changer, a main-line battery, a series of stop-pins carried by the rotary shaft and lying in the path of the keys when 110 depressed, mechanism for holding any key in its depressed position until released by the operator, and circuit-connections whereby on the depression of any key of one set the current impulses cease over the line and when 115 any key of the other set is depressed the current tension is increased, substantially as described. 120

5. A pole-changer, polarized magnets, an escapement, means for actuating said pole-changer and escapement, necessary conductors and connections for connecting the transmitting and receiving stations, a relay at the receiving-station provided with an armature having the necessary contact-points for bringing into play a local battery, and a conductor having electrical connections with said ar- 125 130

mature at one end and having connection through the ground with the center of an electrical generator, substantially as described.

6. A pole-changer and actuating-lever therefor provided with pallets, combined with a rotating shaft provided with teeth co-operating with said pallets for vibrating said pole-changer lever, and a polarized magnet included in the circuit of said pole-changer and an escapement operated thereby governing the rotation of said shaft and consequent operation of said pole-changer, substantially as described.

7. A pole-changer and actuating-lever therefor provided with pallets, combined with a rotating shaft having teeth that co-operate with said pallets for vibrating the said pole-changer lever, and a polarized magnet included in the circuit of said pole-changer and an escapement operated thereby governing the rotation of said shaft and consequent operation of the said pole-changer, and keys for positively arresting said shaft at different angular positions, substantially as described.

8. A pole-changer operated by a pivoted lever having a pair of pallet or ratchet prongs operatively connected with a rotating shaft and a ratchet-wheel, in combination with a pair of polarized magnets located in the line-circuit, an armature, an escapement-wheel and a pallet operatively connected therewith,

an electrical generator and conductors at the transmitting-station, and a pair of polarized magnets, an armature, a pallet, and an escapement-wheel at a receiving-station, substantially as described. 35

9. In a printing telegraphic system, a transmitter and a receiver with a main-line battery at each end of the line, a pole-changer operatively connected with the transmitter, a polar relay operatively connected with the receiver, and switch-connections at each station, whereby one of said batteries is caused to send reversed currents to line and the other to actuate the receiver-magnets, substantially as described. 40 45

10. In a printing telegraphic system, the combination of the following elements at each station: a transmitter, a receiver, a main-line battery, a pole-changer, a polar relay, and a switch having circuit-connections with the transmitter and the receiver, whereby said batteries are alternately used as transmitting or receiving batteries, as required, substantially as described. 50

In witness whereof I hereunto set my hand in presence of two witnesses.
